Primary Examiner — Robert M Spear*Assistant Examiner* — Eliza Bennett-Hattan(74) *Attorney, Agent, or Firm* — Stetina Brunda Garred & Brucker**CLAIM**

The ornamental design for a sports goggle, as shown and described.

DESCRIPTION

FIG. 1 is a front perspective view of the sports goggle of the present invention showing my new design;

FIG. 2 is a front plan view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The dotted lines depict environmental structure and form no part of the claimed design.
